US00D899080S

(12) **United States Design Patent** (10) **Patent No.:** **US D899,080 S**
(45) **Date of Patent:** **** Oct. 20, 2020**

(54) **CONTACT LENS CASE**

(71) Applicant: **Menicon Co., Ltd.**, Nagoya-Shi (JP)

(72) Inventors: **Akihiro Yasuda**, Kasugai (JP); **Keisuke Yamamoto**, Nagoya (JP); **Keiko Yamamoto**, Kasugai (JP)

(73) Assignee: **MENICON CO., LTD.**, Nagoya (JP)

(**) Term: **15 Years**

(21) Appl. No.: **35/506,685**

(22) Filed: **Oct. 30, 2018**

(80) **Hague Agreement Data**

Int. Filing Date: **Oct. 30, 2018**

Int. Reg. No.: **DM/103851**

Int. Reg. Date: **Oct. 30, 2018**

Int. Reg. Pub. Date: **May 3, 2019**

(51) **LOC (12) Cl.** **03-01**

(52) **U.S. Cl.**

USPC **D3/264**

(58) **Field of Classification Search**

USPC ..... D3/203.2, 203.3, 264, 310, 309, 311, D3/312, 313; D9/416, 418, 419, 424, D9/427, 428, 433, 732, 736-762 CPC A45C 11/04; A45C 11/05; B65B 25/008; B65B 51/10

(57) **CLAIM**

The ornamental design for contact lens case, as shown and described.

DESCRIPTION

1. Contact lens case

1.1: Top perspective

1.2: Second top perspective

1.3: Bottom perspective

1.4: Second bottom perspective

1.5: Front

1.6: Back

1.7: Top

1.8: Bottom

1.9: Left

1.10: Right

1.11: Reference Top view showing a state of being covered with a sealing layer

1.12: Cross sectional view taken along line **1.12-1.12** of FIG. **1.11**.

The broken lines depict portions of the contact lens case that form no part of the claimed design.

1 Claim, 11 Drawing Sheets
